UNITED STATES PATENT OFFICE.

WALTER WRIGHT, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,282,515.

Specification of Letters Patent.

Patented Oct. 22, 1918.

Application filed May 15, 1912. Serial No. 697,410.

To all whom it may concern:

Be it known that I, WALTER WRIGHT, a citizen of the United States, residing in New York city, in the county of New York and State of New York, have invented certain new and useful Improvements in Combined Type-Writing and Computing Machines, of which the following is a specification.

This invention relates to a totalizer carriage for adjustably supporting one or more totalizers or computing heads, so as to be movable with the typewriter carriage and relative to the master wheel.

In certain types of combined typewriting and computing machine, such as that described in my application No. 679,851, filed February 26, 1912, the master wheel which successively operates each one of a series of computing wheels in one or more totalizers 20 is stationary while the totalizers move. The movement of the totalizers is obtained by connecting them to the typewriter carriage.

In this case a sub-carriage, for convenience called the totalizer carriage, is connected to move with the typewriter carriage. This totalizer carriage is provided with a clamp whereby one or more totalizers can be secured to the totalizer carriage in such a manner that they can be readily snapped on or 30 off, without sliding them to the end of the clamp, and also so that they can be adjusted along the sub-carriage to vary their position relative to the typewriter carriage, whereby the computing wheels therein can be made to 35 correspond with any group of letter-spaces on the worksheet on the carriage. This enables the totalizers to be adjusted to correspond with a change in the position of a column of numbers to be computed.

40 In order to secure an accurate adjustment, whereby the computing wheels correspond exactly to the letter-spaces, the sub-carriage is provided with a rack, the teeth of which are located at letter-space intervals from 45 each other.

Each of the totalizers is provided with one or more teeth which are adapted to engage in the spaces between the teeth of the rack to determine the adjusted positions of the totalizers.

The clamp shown for securing the totalizers to the sub-carriage is of the spreading type having elongated jaws, one fixed and the other movable. The jaws may be 55 jammed into a dove-tailed groove in each to-

talizer. The movable jaw is controlled by the opposed action of a spring and cam.

Other features and advantages will hereinafter appear.

In the accompanying drawings,

60 Figure 1 is a fragmentary view in front elevation, partly broken away to show the underlying structure.

Fig. 2 is a contracted detail view showing the sub-carriage and its connection to the 65 guide therefor.

Fig. 3 is a fragmentary perspective view of the movable jaw of the clamp.

Fig. 4 is a fragmentary view, partly in section from front to rear, showing the connection of one of the totalizers to the sub-carriage.

Referring more particularly to the separate parts of this invention as embodied in the form shown in the drawings, 1 indicates 75 the typewriter carriage which is supported for longitudinal movement on the typewriter frame 2 in the usual manner. Connected to the typewriter carriage 1 so as to move therewith, in any suitable manner, as 80 by means of a bracket 3, there is provided a sub-carriage 4 which, for the purpose of distinction, may be called a totalizer carriage, in that it is adapted to support one or more totalizers or computing heads 5. The purpose of mounting the totalizers on the sub-carriage 4 so that they will move with the typewriter carriage 1, is to bring each of a series of computing wheels or gears 6 successively into mesh with a master wheel 7, 90 which is rotated variable amounts according to the particular numeral keys struck by the typewriter.

The arrangement for rotating the master wheel may be of any suitable character, such 95 as that described in my application above mentioned.

For the purpose of supporting the totalizer carriage 4, there is provided a guide 8 which is shown in the form of a bracket 100 mounted on the front of the frame 2 and provided with ways 9 into which extend rails 10 bent so as to secure the carriage 4 to the guide. In other words, it may be said that the rails 10 form with the portions of 105 the guide 8, which form the ways 9, interlocking joints which permit a longitudinal sliding movement of the carriage 4, and yet prevent the carriage from moving transversely.

110

The sub-carriage 4 is provided with a body portion shown in the form of an elongated plate 11, on which a clamp 12 is mounted which secures the totalizers 5 to the sub-carriage 4. The clamp 12, in this instance, is shown to comprise a pair of jaws 13 and 14, the former of which is fixed, while the latter is movable. To provide a movable mounting for the jaw 14, it has formed thereon a plurality of pins 15 which engage inclined slots 16 in the body portion 11 of the carriage 4. This slot and pin arrangement is such that a longitudinal movement of the jaw 14 will also cause a transverse movement, so that the jaw 14 moves away from the jaw 13, thereby effecting a spreading action.

Each of the totalizers is provided with a dovetailed socket or groove 17, into which the jaws extend. It will be readily seen that when the jaws 13 and 14 are spread apart, in view of the fact that these jaws are provided with beveled faces to engage the beveled faces of the top and bottom margins of the groove 17, the totalizers will be locked in position on the sub-carriage 4.

To effect the spread action, that is to say, to effect a combined longitudinal and transverse movement of the jaw 14, there is provided a cam lever 18 which is pivotally mounted intermediate its ends and provided with a cam 19, which engages one end of the jaw 14 to move it against the tension of a spring 20 which is secured at one end to the jaw 14, and at the other end to the body portion 11 of the carriage 4. In this instance, the spring is shown normally tending to release the jaw 14 from its clamping position, that is to say, to bring it closer to the jaw 13 while the cam 19 is shown as effecting the clamping action. It may be readily seen, however, that the action could be reversed with the spring effecting the clamping action, and with the cam lever effecting the un-clamping action.

While the clamp 12 will secure the totalizers in any position along the sub-carriage 4, it is advisable to determine the positions of the totalizers so that the computing wheels or gears 6 will be brought in exact register with the master wheel 7 during the successive step-by-step movements of the carriage 1. For this purpose the sub-carriage 4 has formed on its lower edge a rack 21, the distance between the center lines of the spaces between the teeth of which is equal to the distance between successive letter-spaces as determined by the letter-space movement of the typewriter carriage 1.

Each of the totalizers 5 is provided with one or more teeth 22 which are adapted to engage the spaces between the teeth of the rack 21, so as to justify the position of the totalizers on the carriage 4.

Each of the totalizers may also be pro-

vided with an overhanging ledge 23, which engages the top of the body portion 11 of the carriage 4 to prevent the totalizers falling from the sub-carriage when the clamp is manipulated to its releasing condition.

It will thus be seen that there is provided a simple and efficient means, whereby one or more totalizers can be moved along step by step with the typewriter carriage, and yet can be easily adjusted relative thereto, so as to vary the position of the totalizer to correspond with the positions of the column to be computed, which is being typewritten on the worksheet on the typewriter carriage.

It will be seen that the rack and tooth connection of the totalizers with the sub-carriage enables the totalizers to be accurately set at letter-space intervals along the sub-carriage, whereby the register of the computing wheel 6 with the master wheel 7 will be assured. At the same time if the totalizer is properly positioned with reference to the teeth of the rack 21, it can be directly applied to the clamp, without sliding it on from the end of its support. The result is that additional intermediate totalizers can be placed at any time without disturbing the adjustment of any already in position.

Variations may be resorted to within the scope of the invention, and portions of the improvements may be used without others.

Having thus described my invention, I claim:

1. The combination with a typewriter carriage, of a sub-carriage connected thereto, an elongated clamp on said sub-carriage, one or more totalizers or computing heads mounted on said sub-carriage, and a spring and cam working in opposition to each other to effect the securing and releasing action of said clamp.

2. The combination with a typewriter carriage, of a sub-carriage connected thereto, an elongated clamp on said sub-carriage, one or more totalizers or computing heads mounted on said sub-carriage, said clamp having a movable jaw, a spring for moving said jaw in one direction, and a cam acting against the tension of said spring to move said jaw in the opposite direction.

3. The combination with a typewriter carriage, a totalizer carriage secured to move with said typewriter carriage, a clamp on said totalizer carriage, a guide for said totalizer carriage, rails on said totalizer carriage engaging said guide, and one or more totalizers adjustably mounted along said clamp.

4. The combination with a typewriter carriage, of a totalizer carriage connected to move with said typewriter carriage, an elongated clamp mounted on said totalizer carriage, to clamp either one or more totalizers adjustably mounted along said totalizer carriage, said clamp comprising a pair of jaws, each of said totalizers having a groove

- therein, and means for spreading said jaws to grip the sides of said groove.
5. The combination with a typewriter carriage, of a totalizer carriage connected to move with said typewriter carriage, an elongated clamp mounted on said totalizer carriage, to clamp either one or more totalizers adjustably mounted along said totalizer carriage, said clamp comprising a pair 10 of jaws, each of said totalizers having a groove therein, means for spreading said jaws to grip the sides of said groove, and means for moving said jaws toward each other.
15. 6. The combination with a typewriter carriage, of a totalizer carriage connected to move with said typewriter carriage, an elongated clamp mounted on said totalizer carriage, one or more totalizers adjustably 20 mounted along said totalizer carriage and secured thereto by said clamp, said clamp comprising a fixed jaw and a movable jaw, a spring tending to move said movable jaw toward said fixed jaw, and a cam for moving 25 said movable jaw away from said fixed jaw.
7. The combination with a typewriter carriage, of a totalizer carriage connected to move with said typewriter carriage, an elongated clamp mounted on said totalizer carriage, one or more totalizers adjustably 30 mounted along said totalizer carriage and secured thereto by said clamp, said clamp comprising a fixed jaw and a movable jaw, said movable jaw having an inclined pin and 35 slot connection with said totalizer carriage, so that a longitudinal movement of said movable jaw will cause a transverse movement thereof, and means for moving said movable jaw.
40. 8. The combination with a typewriter carriage, of a totalizer carriage connected to move with said typewriter carriage, an elongated clamp mounted on said totalizer carriage, one or more totalizers adjustably 45 mounted along said totalizer carriage and secured thereto by said clamp, said clamp comprising a fixed jaw and a movable jaw, said movable jaw having an inclined pin and slot connection with said totalizer carriage, so that a longitudinal movement of 50 said movable jaw will cause a transverse movement thereof, a spring connected to said movable jaw at one end and to said totalizer carriage at its other end, and a cam 55 lever engaging the end of said movable jaw so as to be capable of moving said movable jaw against the tension of said spring.
9. The combination with a typewriter carriage, of a sub-carriage connected to move 60 with said typewriter carriage, a guide for said sub-carriage, rails on said sub-carriage engaging said guide, an adjustable totalizer connectible to move with said sub-carriage and with said typewriter carriage, said totalizer having a groove therein with top 65 and bottom recessed portions, and an elongated clamp mounted on said sub-carriage and spreadable in said groove to secure said totalizer to said sub-carriage, at any adjustment of said totalizer.
10. The combination with a typewriter carriage, of a sub-carriage connected to move with said typewriter carriage, projecting angle rails on said sub-carriage, a fixed 70 guide having projecting portions interlocking with said angle rails to form ways so as to permit a longitudinal movement of said sub-carriage with said typewriter carriage and prevent transverse and vertical movements thereof, a totalizer adjustably 75 connected to said sub-carriage, and means for securing said totalizer to said sub-carriage.
11. The combination with a typewriter carriage, of a totalizer carriage connected 80 to said typewriter carriage, one or more totalizers, and an elongated clamp on said totalizer carriage arranged to directly receive a totalizer at any letter-space interval along the typewriter carriage.
12. The combination with a typewriter carriage, of a totalizer carriage connected 85 to and traveling concomitantly with said typewriter carriage, one or more totalizers, and a clamping connection having a part 90 extending the entire length of said totalizer carriage enabling the direct snapping on of a totalizer to correspond with any letter-space interval of said typewriter carriage.
13. The combination with a totalizer and 95 a support, of a fixed bar forming a part of said support on which the totalizer may be caught by direct application thereto, and along which the totalizer may be adjusted, and a second movable bar extending along 100 the first and adapted to be moved to engage and hold the totalizer to said support.
14. The combination with a totalizer comprising hooked members, of a support along 105 which the totalizer may be adjusted, a fixed bar forming part of said support, and adapted to be engaged by said hooked members to catch the totalizer, and a second bar extending along and movable on said support adapted to be moved to position to engage 110 other of said hooked members and lock the totalizer thereby; said bar also movable to a position to permit the totalizer to be applied and adjusted to the support at the desired position freely and then movable to 115 an effective position to hold said totalizer.
15. The combination with a totalizer and 120 a support along which the totalizer is adjustable, of a fixed bar forming a part of said support on which the totalizer may be caught by direct application thereto, and a second movable bar extending along the first and adapted to hold the totalizer to said support.
16. The combination with a totalizer com- 125

- prising hooked members, of a support, a fixed bar forming a part of said support adapted to engage certain of said hooked members to catch the totalizer, and a second 5 bar movable on said support adapted to be moved to position to engage other of said hooked members and lock the totalizer thereby; said bar also movable to a position to permit the totalizer to be adjusted to the 10 support at the desired position freely, and then movable to an effective position to hold said totalizer.
17. The combination with a totalizer and a support therefor, of two bars on said support forming clamping members, engaging members on said totalizer to coöperate with said clamps, and a cam for moving one of said clamps to effective position to lock the totalizer in place.
18. The combination with a totalizer and a support, of two bars on said support, one of said bars being fixed, engaging members on the totalizer for engaging said bars, and means for moving one bar from a position 25 completely out of the way of said engaging members and also moving it to a position to engage said members and lock the totalizer to the support.
19. The combination with a totalizer and a support, of extensions on said totalizer having inclined faces, a fixed bar, said support having a face coöoperating with one of said inclined faces, a movable bar on said support having a face coöoperating with another of said inclined faces, said movable 30 bar settable at a position clear of the totalizer extensions to allow the totalizer to be applied and adjusted to the support, and a lock for setting said movable bar at a position to lock the totalizer to said support.
20. The combination with a totalizer and a support, of extensions on said totalizer having inclined faces, a fixed bar, said support having a face coöoperating with one of 35 said inclined faces, a movable bar on said support having a face coöoperating with another of said inclined faces, said movable bar settable at a position clear of the totalizer extensions to allow the totalizer to be applied and adjusted to the support, a spring 40 normally tensioning said movable bar in ineffective position, and a lever cam for shifting said bar to effective position and locking it there.
21. In a computing machine, the combination with a totalizer and a support therefor, of hooks on said totalizer, a bar adapted to be engaged by certain of said hooks, a second bar adapted to be engaged by others of 45 said hooks, means for moving one of said bars parallel to the other and into and out of engaging position with its coöoperating hooks on the totalizer to lock the totalizer, and a rack adapted to coöperate with a part of said totalizer to keep the totalizer from 50 being moved transversely with the locking bar.
22. In a computing machine, the combination with a totalizer and a support therefor, of hooks on said totalizer, a bar adapted to be engaged by certain of said hooks, a second bar adapted to be engaged by others of 55 said hooks, means for moving one of said bars parallel to the other and into and out of engaging position with its coöoperating hooks on the totalizer to lock the totalizer, pins on one of said bars adapted to coöperate with slots inclined thereto for guiding it into and out of effective position, and a handle for moving said bar transversely of said slots to 60 so release or engage said totalizer.
23. In a computing machine, the combination with a totalizer comprising hooks, of two bars, each adapted to engage certain of said hooks, studs on one of said bars adapted to coöperate with diagonal slots for moving said last-named bar into and out of coöperation with its hooks, a rack coöoperating with said totalizer adapted to prevent transverse movement thereof when the bar is moved on 65 its studs, a spring normally holding said bar in its ineffective position, and a cam handle adapted to move said bar to its effective position and lock it there.
24. The combination with a typewriter carriage, of a sub-carriage connected thereto, and a single elongated clamp on said sub-carriage, to clamp either one or more detachable totalizers or computing heads mounted on said sub-carriage, said clamp being arranged to lock to or release from said carriage all totalizers that may be mounted thereon.
25. The combination with a typewriter carriage having means for carrying one or 70 more adjustable totalizers, of means for limiting the positions of said totalizers to points located at predetermined letter-space intervals from each other, and universal means for locking either one or more of said totalizers in their adjusted positions relative to 75 said carriage.

WALTER WRIGHT.
